UNITED STATES PATENT OFFICE.

WILLIAM OSCAR KENNINGTON, OF LONDON, ENGLAND, ASSIGNOR TO A C SPARK PLUG COMPANY, OF FLINT, MICHIGAN, A COMPANY OF MICHIGAN.

ELECTRICAL COUPLING.

Application filed April 14, 1925, Serial No. 23,137, and in Great Britain January 12, 1925.

This invention has reference to electrical couplings, clips or connections more particularly but not exclusively adapted for connecting the high tension cable to the terminal post of sparking plugs.

The objects of my invention are to provide an improved coupling of simple construction which may be economically produced, will ensure good electrical contact, and one which will be mechanically able to stand the severest vibration to which it is likely to be subjected in practice.

Referring to the accompanying drawings:—

15 Figure 1 is an elevation of one convenient form of clip in accordance with the present invention as applied to a sparking plug and high tension cable, and

20 Figure 2 is an enlarged view of the clip alone in unstressed position.

In carrying the invention into effect in one form by way of example adapted for attaching a high tension cable to a sparking plug terminal post, I form the clip of spring wire which is bent for about two and a half turns to form a ring *a* (Figure 2).

25 The two legs *b*, *c* terminate respectively in a loop or eye *d* and two loops or eyes *e*, *f*, all these eyes being an easy fit upon the terminal post *g* to which they are to be applied. The ring *a* when in unstressed condition (Figure 2) is of such internal diameter that when the cable *h* has been stripped back and the conductors *i* bent back over the 30 surface as shown in Figure 1, the cable may be inserted readily, accompanied if necessary by a twisting of the clip relatively to the cable end.

35 After the cable end has been inserted in the ring the two legs of the coupling are pressed together to cause the eyes *d* and *e*, *f* carried thereby to meet in such a manner as to permit of their being pushed over the

terminal post or the like *g* and upon being released the cable will be securely gripped by the spring ring of the coupling clip and the terminal post also securely gripped by the aforesaid eyes.

Under this invention I am able to provide a coupling clip which will grip the cable 45 tightly when the legs are pressed together and by virtue of the legs being stressed when the coupling clip is in position upon the terminal post the latter is firmly gripped by the aforesaid eyes.

50 It will be understood that the form described above is given by way of example only and may be modified. For example it is not essential to provide two and a half turns for the ring or the three eyes which 55 are shown, but the arrangement described is preferred.

Having now described my invention what I claim as new and desire to secure by Letters Patent is:—

60 In combination, a conductor wire, a spark plug including a projecting electrode, and a connector electrically connecting the wire to the electrode and consisting of a wire having a loop therein adapted to be loosely 65 slipped over the end of the conductor wire and engaging tightly about the same when in connecting position, the end portions of the wire having loops bent therefrom, one being a double loop and the other having 70 a loop portion received between the convolutions of the double loop, tending to spread apart therefrom to thereby clamp the electrode when in connecting position thereon, the axes of said loops when in connecting 75 position substantially coinciding and substantially intersecting that of the end portion of the conductor wire.

80 In testimony whereof I have signed my name to this specification.

WILLIAM OSCAR KENNINGTON.
